UNITED STATES PATENT OFFICE.

EDWARDS F. SCHERMERHORN, OF BROOKLYN, NEW YORK, ASSIGNOR TO THE RAIL JOINT COMPANY, OF NEW YORK, N. Y., A CORPORATION OF NEW YORK.

INSULATED RAIL JOINT.

Application filed May 4, 1925. Serial No. 27,941.

To all whom it may concern:

Be it known that I, EDWARDS F. SCHERMERHORN, a citizen of the United States, residing at Brooklyn, in the county of Kings and State of New York, have invented certain new and useful Improvements in Insulated Rail Joints, of which the following is a specification.

This invention relates to an improvement in insulated rail joints, and primarily has in view an economic use of the metal in the formation of the joint bar, resulting in a very much lightened construction for the joint, while at the same time providing a joint bar improved in the modulus of its head section as well as in its total moment, so as to possess the requisite strength and stiffness for resisting the load and lateral forces imposed thereon.

Ordinarily, in the fabrication of insulated rail joints, the rail joint bars which fit the fishing spaces of the rails are rather heavy and somewhat massive in construction in order not only to provide the necessary strength and stiffness but also to afford ample bearing area in the bolt holes for the insulating bushings. While these factors are duly taken into consideration by the present invention, a distinctive feature of the latter resides in so deforming the joint bar, preferably at the outer side of its web, as to materially decrease the amount of metal in the joint bar. This materially lightens it, yet involves such a distribution of metal as to secure adequate stiffness and to permit the web of the bar to be disposed quite close to the web of the rail so that the bolt insulating bushings will have extended or adequate bearing areas in the bolt holes, and thereby will be protected from cutting or shearing forces; consequently prolonged in life.

With these and other objects in view which will appear to those familiar with the art as the nature of the invention is better understood, the same consists in the novel construction, combination and arrangement of parts hereinafter more fully described, illustrated and claimed, and while the structural features of the invention are necessarily susceptible of a wide range of modification without departing from the spirit thereof, a preferred and practical em-

bodiment is shown in the accompanying drawings, in which

Figure 1 is a sectional perspective view of an insulated rail joint constructed in accordance with the present invention.

Figure 2 is a view similar to Figure 1 showing the bolt fastenings and the outer filler and abutment member removed, thereby exposing the deformed structural characteristics of the outer side of the web of the joint bar.

Figure 3 is a vertical cross sectional view on the line 3—3 of Figure 1.

Figure 4 is a detail horizontal sectional view on the line 4—4 of Figure 3.

In carrying forward the present invention the primary feature thereof is to entirely change the plan of metal distribution in making the joint bar. That involves a substantial lightening of the weight of the bar, and preferably is accomplished by rolling the joint bar designated by the numeral 1 with deformations in the outer sides of its web 2. These deformations obviously could assume different forms or shapes but in the preferred embodiment consist in making the outer side of the web 2 of the joint bar of corrugated formation comprising the upright rib members 3 and the cavities or reducements 4 alternating therewith. The rib members 3 represent the normal wall thickness for the web of the bar while the cavities or reducements 4 form subnormally thinned wall portions. In other words at spaced locations the web of the joint bar is left with normal wall portions 3, and in other spaced locations as at 4 substantial quantities of metal are removed from the web of the joint bar leaving at such places subnormally thinned wall portions, thereby substantially and materially lightening the joint bar. Furthermore, it will be observed from the drawings that the cavities or grooves producing the subnormally thinned wall portions extend to and preferably somewhat past the fillets at the upper and lower corners of the bar web, thereby conserving at such points the reinforcing effect of the brackets of metal formed by the upper and lower ends of the wall or rib members 3 which merge respectively into the head and foot portions of the bar. This plan of metal distribution

permits substantial economy and saving in the use of metal, and at the same time obtains the proper distribution of metal whereby adequate head, foot and web strength may be maintained.

Furthermore, by confining the deformation of the web of the bar to the outside thereof, the bar may be so shaped as to bring its web quite close to the web of the rail so that the bolt holes 5 through the web of the bar afford ample bearing area for the insulating bolt-bushings 6 which receive the joint bolts 7.

In fabricating an insulated rail joint embodying a joint bar having the structural characteristics described the usual head and base insulation 8 and 9 respectively are employed, and the joint structure is completed, by associating with each joint bar an outer 20 filler member 10, insulating washer 11 and metal washer plate 12.

The outer filler member 10 may be made of insulating material or of a cheap quality of steel and is in the form of a plate or bar 25 having a flat outer face 13 constituting an abutment against which flatly bears the insulating washer 11 and at its inner side the filler member is corrugated producing alternate ribs 14 and channels 15 which are complements of and register with the ribs 3 and grooves 4 respectively of the corrugated outer side of the web 2 of the rail joint bar. In brief, the inner side of the filler member 10 is corrugated to correspond to and interlock with the correspondingly corrugated outer side of the web of the joint bar so that the filler member will constitute a light but substantial abutment against which the insulating washers 11 are clamped by the metal washers 12 when the nuts 16 of the bolts are tightened.

From the construction described it will be seen that not only is the joint materially lightened in weight throughout but a very 45 thorough and satisfactory insulation for the joint is permitted while at the same time a very extended and ample bearing area is provided for the bolt bearing bushings 6 in the bolt holes 5 of the joint bars, which bolt holes register with the bolt holes 5^a in the outer filler members 10. In the embodiment shown in the drawings the joint bar illustrated is of the well known continuous type but it will of course be understood that the 55 improvements are applicable to joint bars of the angle type, and while the outer filler member 10 is shown as a continuous strip or bar the same may be made in separate pieces, and other minor modifications resorted to 60 without departing from the spirit or sac-

rificing any of the advantages of the invention.

I claim:

1. An insulated rail joint including a joint bar insulated at its inner side from the rail and having the outer side of its web deformed to produce subnormally lightened web portions, and clamping means interlocking with said deformed part of the bar web. 65

2. An insulated rail joint including a joint bar insulated at its inner side from the rail and having the outer side of its web deformed to produce subnormally lightened web portions, and insulated clamping means interlocking with said deformed part of the bar web. 70

3. An insulated rail joint including a joint bar insulated at its inner side from the rail and having its outer side formed with corrugations producing subnormally thin 80 portions in the web, and clamping means interlocking with the corrugated outer side of the bar.

4. An insulated rail joint including a joint bar insulated at its inner side from the rail and having its outer side deformed to produce vertically disposed and alternately arranged depressions forming subnormally thin web portions, and clamping means interlocking with the outer side of the 90 bar web. 85

5. An insulated rail joint including a joint bar insulated at its inner side from the rail and provided at its outer side with cavities forming subnormally thinned web portions, a filler member having ribs engaging and interlocking with the cavities of the bar web, and means for clamping the filler member in place. 95

6. An insulated rail joint including a joint bar insulated at its inner side from the rail and provided at its outer side with cavities forming subnormally thinned web portions, a filler member having ribs engaging and interlocking with the cavities of the bar web, and insulated means for clamping the filler member in place. 100

7. An insulated rail joint including a joint bar insulated at its inner side from the rail and provided at the outer side of its web with alternating portions respectively of normal and subnormal thickness, a filler member or plate provided at its inner side with alternating ribs and channels interlocking with the deformed outer side of the bar web, and insulated bolt clamping means engaging the filler member or plate. 110

In testimony whereof I hereunto affix my signature.

EDWARDS F. SCHERMERHORN.
